UNITED STATES PATENT OFFICE.

CHESTER E. WARNER, OF BERWYN, ILLINOIS, ASSIGNOR TO BENJAMIN ELECTRIC MANUFACTURING COMPANY, OF CHICAGO, ILLINOIS, A CORPORATION OF ILLINOIS.

PULL-SWITCH SOCKET.

Application filed September 7, 1920. Serial No. 408,579.

To all whom it may concern:

Be it known that I, CHESTER E. WARNER, a citizen of the United States, residing at Berwyn, in the county of Cook and State of Illinois, have invented new and useful Improvements in Pull-Switch Sockets, of which the following is a full, clear, concise, and exact description, reference being had to the accompanying drawing, forming a part of this specification.

My invention relates to electrical connector devices and more specifically to pull switch sockets.

One of the objects of my invention is to provide an improved pull switch socket, which will be durable and efficient in operation, simple in construction and easy to assemble.

Further objects will appear from the detailed description to follow and from the appended claims.

In the drawings, in which one embodiment of my invention is shown;

Fig. 1 is a top plan view of an angle pull switch socket having the cap removed;

Fig. 2 is a section on the line 2—2 of Fig. 1;

Fig. 3 is a section on the line 3—3 of Fig. 5;

Fig. 4 is a section on the line 4—4 of Fig. 2;

Fig. 5 is a section on the line 5—5 of Fig. 1;

Fig. 6 is a section on the line 6—6 of Fig. 2;

Fig. 7 is a detail perspective view of part of the switch mechanism;

Fig. 8 is a section on the line 8—8 of Fig. 1;

Fig. 9 is a section on the line 9—9 of Fig. 2; and

Fig. 10 is a section on the line 10—10 of Fig. 2.

The angle pull switch socket shown in the drawing comprises in a general way, shell and center contacts 10 and 11 for engagement with the contacts of an insertable device, wiring terminals 12 and 13 for the contacts 10 and 11 respectively, a pull switch mechanism 14 for controlling the circuit between the center contact 11 and wiring terminal 13, a substantially cylindrical insulating base for supporting the contacts 10 and 11, the wiring terminals 12 and 13, and the switch mechanism 14, and pro-

viding the necessary insulation therebetween, and a sheet metal shell casing 16 surrounding the insulating base 15 and threaded shell contact 10. An insulating fibre cup or sleeve 17 is provided between the shell contact 10 and casing 16.

The threaded shell contact 10 is always electrically connected with its wiring terminal 12, by means of a screw 18, the head of which engages the flange 19, (Fig. 3) of the threaded shell contact, and the shank of which is threaded into the binding plate 20 (Fig. 1) of the wiring terminal 12.

The switch mechanism 14 controls the circuit between the yielding contact members 21 and 22 (Fig. 8) the yielding contact 22 being always electrically connected with the center contact 11 by means of the tubular eyelet 23, the other yielding contact 21 being always electrically connected with the wiring terminal 13, by means of a screw 24, which is threaded into the binding plate 25 of the wiring terminal 13, to clamp the binding plate down against the base of the spring contact 21, and firmly hold the binding plate and spring contact in place from the insulating base 15. The screw 23 not only serves to electrically connect the spring contact 22 and center contact 11, but also serves to hold these parts in place on the insulating base.

The switch mechanism 14 is located in a recess 26 in the insulating base 15. This switch mechanism comprises a U-shaped switch arm or blade 27 of conducting material, oscillatable about an axis parallel to the axis of the socket, and movable into and out of engagement with respect to the yielding contacts 21 and 22, a coil compression spring 28 bearing on the end of the switch blade 27, and shiftable past a dead center line to cause a quick action of the switch arm 27, a swing shifting link 29 surrounded by the spring 28 and having one end slidable in a slot 30 in the U-shaped switch arm 27, a rotatable barrel-cam 31 having an elliptical groove 32 for engagement with one end of the spring shifting link 29, a pull chain 33 for operating the switch mechanism, a switch lever 34 to which the pull chain 33 is secured, ratchet mechanism 35 whereby the oscillating movement of the switch lever 34 causes a step-by-step rotary movement of the barrel-cam 31 to cause oscillation of the switch arm 27, and a switch frame 36 which

may be an integral sheet metal stamping, supporting the switch arm 27, the lever 34 and the various other parts of the switch mechanism associated therewith. The elliptical groove 32 may be considered as comprising two helical cam track portions, one of which shifts the link 29 in one direction and the other of which shifts the link in the other direction.

- 10 For returning the switch lever 34 after it has been operated by the pull chain 33, a coil torsion spring 37 is provided, one end of which is connected to the switch frame at 38, and the other end of which is connected 15 at 39 (Figs. 2 and 3) to an insulating disc 40, forming part of the lever. The switch frame 36 is secured in place in the recess by means of a screw 41, extending through an opening in the insulating base 15 and threaded into the base of the switch frame. The switch arm 27 is supported in its movement of oscillation by means of a pivot pin 42 mounted in ears 43 of the switch frame 36, and extending through openings in the arms 20 of the U-shaped switch blade 27. The lever 34 and the barrel-cam 31 are mounted for movements of oscillation and step-by-step rotation on a switch shaft 44 mounted in the switch frame 36.
- 25 The groove 32 in the barrel-cam 31 is a continuous elliptical groove so that the continuous step-by-step rotation of the barrel-cam 31 through a complete rotation of 360 degrees brings the spring shifting link 29 back 30 to the point from which it started. The construction of the ratchet 35 is such that each operation of the pull chain 33 will cause the barrel-cam 31 to move through 180 degrees, to shift the swinging spring shifting link 29 35 from one extreme position to the other to cause the pivoted switch blade 27 to move from off to on position, or vice-versa.

The spring shifting link 29 is provided with a central projection or lug 45, which 40 extends into the elliptical groove 32, this lug 45 remaining in the groove 32 as the barrel-cam 31 is rotated, and causing the shifting of the link. In order to keep the link 29 from slipping off sideways, it is provided 45 with arms 46 (Fig. 5) which embrace the barrel-cam. These arms do not engage in the groove, as neither arm is ever in alignment with the plane of the groove 32, during any part of the movement of the barrel-cam.

50 As shown in Fig. 9, the arms of the switch blade 27 straddle the barrel-cam, the switch blade 27 in its middle position lying substantially in a plane perpendicular to the axis of the barrel-cam, one end of the spring shifting member 29 having a movement along a line parallel to the axis of the barrel-cam and of the switch lever or chain rail 34.

55 The ratchet mechanism 35 comprises a disc ratchet member 47 (which may be integral with the barrel-cam 31) having

ratchet teeth 48 which cooperates with ratchet depressions 49, in the fibre disc 40.

The pull chain 33 is secured to a hook-shaped portion 50 of the chain rail which forms part of the lever. For limiting the 70 return movement of the pull chain under the action of the return spring 37, a lug or stop 51 is struck up from the switch frame 36, in position to be engaged by the hook member 50 on the return movement of the chain rail (Fig. 10). The chain rail is secured to the fibre disc 40 by means of lug 52 integral with the stamping from which the chain rail is formed and bent over the edge of the disc 40 into recesses in the disc. (Figs. 2 and 6). 75

To operate the switch the pull chain 33 is pulled down to move the switch lever 34 through 180 degrees, causing a corresponding movement of the barrel-cam 31 through the ratchet mechanism 35. This movement 80 of the barrel-cam 31 through 180 degrees shifts the spring shifting link 29 from one extreme position to the other and shifts the switch arm 27 from off to on position or vice-versa, the movement of the switch arm 27 on to the swinging link after the spring shifting member 29 has passed the dead center line being effected, under the action of the compressed spring 28.

85 While I have shown but one embodiment of my invention, it may be embodied in other forms as covered and defined by the appended claims.

What I claim as new and desire to secure by Letters Patent of the United States 90 is:

1. A pull switch socket comprising an oscillatable switch blade, a spring bearing on said switch blade, a spring shifting member for shifting said spring past a dead center 105 to cause oscillation of the switch blade, an oscillatable switch lever and means for shifting said spring shifting member substantially longitudinally of the axis of said switch lever, said means comprising a cylindrical cam coaxial with said switch lever, said cylindrical cam having an elliptical groove in its cylindrical surface.

2. A switch comprising a pivoted switch blade oscillatable back and forth, means for causing said switch blade to oscillate back and forth, comprising a rotatable cylindrical cam having an oval cam track on its cylindrical surface and rotatable therewith, said switch blade in its middle position lying substantially in a plane perpendicular to the axis of said cylindrical cam.

3. A switch comprising a U-shaped switch blade oscillatable back and forth, means for causing said switch blade to oscillate back and forth comprising a cylindrical barrel-cam straddled by the arms of said U-shaped switch blade.

4. A switch mechanism comprising a switch blade oscillatable back and forth, a 130

spring acting on said switch blade, and means for shifting said spring back and forth to cause oscillation of the switch blade comprising a rotatable member having a 5 cylindrical surface provided with a cam track having a helical portion, said surface and cam track being part of and being rotatable with said rotatable member.

5. A switch mechanism comprising a 10 switch blade oscillatable back and forth, a spring acting on said switch blade, and means for shifting said spring back and forth to cause oscillation of the switch blade comprising a rotatable member having a 15 cylindrical surface provided with a cam track having a helical portion and a ratchet member coaxial with said cylindrical cam member for actuating it.

6. A switch mechanism comprising a

switch blade oscillatable back and forth, a 20 spring acting on said switch blade, and means for shifting said spring back and forth to cause oscillation of the switch blade comprising a rotatable member having a 25 cylindrical surface provided with a cam track having a helical portion lying substantially on one semi-cylindrical portion of the cylindrical member, and a helical portion lying on the other semi-cylindrical portion of the cylindrical member, the two helical portions being continuous with each other to form a continuous track around the cylindrical member, whereby each half revolution of the cylindrical member causes oscillation of the switch blade. 30 35

In witness whereof, I have hereunto subscribed my name.

CHESTER E. WARNER.
